UNITED STATES PATENT OFFICE.

EDGAR J. PACE, OF LOS ANGELES, CALIFORNIA, ASSIGNOR TO NATIONAL STREET AND STATION INDICATOR COMPANY, OF LOS ANGELES, CALIFORNIA, A CORPORATION OF CALIFORNIA.

SWITCH MECHANISM.

1,119,719.

Specification of Letters Patent.

Patented Dec. 1, 1914.

Application filed December 10, 1912, Serial No. 735,954. Renewed October 22, 1914. Serial No. 868,124.

To all whom it may concern:

Be it known that I, EDGAR J. PACE, a citizen of the United States, residing at Los Angeles, in the county of Los Angeles, State 5 of California, have invented new and useful Improvements in Switch Mechanisms, of which the following is a specification.

This invention relates to certain improvements in my switch mechanisms for which 10 I have made application for U. S. Letters Patent on December 23rd, 1911, bearing S. N. 667,439; and the improvements consist generally in certain changes for greater efficiency which will be hereinafter fully described and pointed out.

Fundamentally, the present improvement consists in the use of a switch needle mechanism in combination with two main or primary magnets, one arranged on each side.

20 In my formerly described mechanism, of the application above referred to, I have used a pivoted magnetic needle and a single actuating magnet spaced therefrom, the magnetic lines of force being conducted 25 from the actuating magnet to the pivoted needle through a track plate over which the whole device passes. Although the fundamentals of operation of this formerly described device are precisely the same as of 30 the device about to be described, I have found upon repeated practice that the first form does not operate with absolute uniformity in both directions of travel; that is, it will operate with more certainty and 35 with generally better efficiency when the movement causes the needle to pass over the track plate after the magnet, rather than when the movement is in the opposite relative direction and causes the needle to first 40 come over the track plate. To obviate this difficulty I have devised a double arrangement, symmetrical with respect to a central plane perpendicular to the line of movement; so that the device acts equally well 45 when moving in either direction.

The foregoing is the fundamental advantage of the present specific form of switch mechanism; but there are other advantages which will be pointed out in the following 50 detailed specification.

I have shown in the accompanying drawings my now preferred form of device and I have also shown a diagram indicating the nature of the magnetic action.

55 In the drawings: Figure 1 is a side ele-

vation illustrating the complete arrangement of the whole mechanism. Fig. 2 is a diagram illustrating the magnetic action thereof. Fig. 3 is a detail showing the arrangement of the needle and its magnetizing 60 coil.

In the drawing 10 may designate the body of a car on which the movable portions of the switch mechanism are carried, and 11 may designate the track plate over which 65 the movable portions pass.

12 designates the main or primary magnets which are supported from the car body 10, and 13 designates generally the switch mechanism, including the movable pivoted 70 needle 14 and its magnetizing coil 15.

Each of the magnets 12 may be of any desired design and of sufficient magnetic strength to cause the operation of the switch device. The lower poles of the magnets may 75 preferably be provided with horizontal magnetic pieces 20 from which depends other magnetic pieces 21 hanging in close proximity to the track plate. The object of the attachments to the lower poles of the magnets 80 12 is to effect efficient transmission of the magnetism into the track plate 11. The lower extremities of the magnets are of same polarity; so that the track plate is magnetized 85 with like polarities at its ends and with a central consequent pole. The lines of force through the system are generally indicated in Fig. 2; and it will be seen that there is a fairly uniform field with lines running vertically above the central portion of the 90 track plate 11. This central field will include and act upon the whole of the needle 14, repelling one end of the needle and attracting the other end toward the track plate. This action causes very efficient operation 95 of the needle.

The switch mechanism proper, including the movable needle and the switch operated thereby, is composed as is best shown in Figs. 1 and 3. There is provided a suitable 100 non-magnetic inclosing casing 30 in which is suspended the magnetizing coil 15 on suitable supports 31. The needle 14 is suitably pivoted at 32 within the magnetizing coil and normally stands in about the position 105 illustrated in Fig. 3.

A small rubber buffer 33 is provided to limit movement of the needle in the direction opposite to that indicated. When the needle passes over the track plate, and is 110

subjected to the magnetic influence heretofore described, it is moved to the position shown in Figs. 1 and 2; and its movement causes the operation of the switch 35. Switch 5 35 may be connected with the needle in any desired manner; but I may prefer its operation through the medium of suitable gears 36 and 37. The switch itself is formed by a contact 38 on the gear 37, or on a part carried thereby, adapted to engage with a contact arm or finger 39 mounted upon a small frame 40 carried by the magnetizing coil 15. The connecting wires to the various parts run to binding posts 41 which are mounted 10 on the insulated block 42 at the upper side of casing 30.

I have shown the switch mechanism as being arranged higher above the track plate than are the magnets 12. The switch mechanism 20 may be arranged as high as is possible to prevent it striking any obstacles upon the track; and when it is at any great height a magnetic conductor may be hung from the track plate to the needle. (This expedient 25 is illustrated in the application hereinbefore referred to.) In my application, hereinbefore referred to, the normal position of the needle 14 was in a direction inclined oppositely to the inclination shown in Fig. 1; but 30 I now prefer to have the needle normally in the position shown in Fig. 2, being held therein by any suitable arrangement, such as a slight gravitational balance tending to return it to that position.

Having described my invention, I claim: 35 1. In combination, two separate and distinct sources of magnetism spaced apart from each other, a magnetically movable needle between the two sources, and a magnetic conductor, the said sources and needle being movable relative to the conductor into and out of proximity thereto.

2. In combination, two separate and distinct sources of magnetism spaced apart 45 from each other, a magnetized pivoted needle between the two sources, and a magnetic conductor, the said sources and needle being movable relative to the conductor into and out of proximity thereto.

3. In combination, a pair of magnets spaced apart, a magnetically movable needle placed between them, and a magnetic conductor, said sources and needle being movable together in such relation to the conductor 50 that they may be moved simultaneously into proximity to the conductor.

4. In combination, a pair of magnets spaced apart, a centrally pivoted needle placed midway between the magnets, a magnetizing coil for the needle, and a magnetic conductor over which the magnets and the needle are adapted to pass, the relative arrangement of the parts being such that the

magnets and needle may all be moved simultaneously into proximity to the conductor. 65

5. In combination, a pair of magnets spaced apart, a centrally pivoted needle placed midway between the magnets, a stationary magnetizing coil surrounding the needle, and a magnetic conductor over which 70 the magnets and the needle are adapted to pass, the relative arrangement of the parts being such that the magnets and needle may all be moved simultaneously into proximity to the conductor.

6. In combination, a pair of magnets spaced apart, a centrally pivoted needle placed midway between the magnets, a magnetizing coil for the needle, the needle being pivoted on an axis transverse to the magnetic axis of the coil, and a magnetic conductor over which the magnets and the needle are adapted to pass, the relative arrangement of the parts being such that the magnets and needle may all be moved simultaneously into proximity to the conductor. 80

7. In combination, a pair of magnets spaced apart horizontally and arranged with like poles below, a needle mechanism arranged midway between the two magnets, 90 said mechanism comprising an annular magnetizing coil, a needle gravitationally balanced on and symmetrically arranged with respect to a pivot transverse of the magnetic axis of the coil, and a magnetic conductor over which the electro-magnets and the needle mechanism are adapted to pass, the conductor being inductively energized by the electro-magnets to produce a central consequent pole and by virtue of such magnetization moving the needle by magnetic traction. 95

8. In combination, a pair of magnets spaced apart horizontally and arranged with like poles below, a magnetically movable 105 needle pivoted midway between the two magnets, and a magnetic conductor over which the magnets and needle may pass, the conductor being of such dimensions that when the needle is over its central portion the magnets will be over its ends. 110

9. In combination, two separate and distinct sources of magnetism spaced apart from each other, a magnetically actuatable mechanism between the two sources, and a magnetic conductor, the said sources and mechanism being movable relative to the conductor into and out of proximity thereto. 115

In witness that I claim the foregoing I have hereunto subscribed my name this 4th 120 day of December, 1912.

E. J. PACE.
